UNITED STATES PATENT OFFICE

EDWARD E. HUNTINGTON, OF TOLEDO, OHIO, ASSIGNOR TO THE WILLYS-OVERLAND COMPANY, OF TOLEDO, OHIO, A CORPORATION OF OHIO

MANIFOLD CONSTRUCTION

Application filed September 4, 1926. Serial No. 133,685.

This application relates to engine manifolds and more particularly to manifolds for internal combustion engines, in which are incorporated auxiliary devices for facilitating 5 the starting of the engine.

One of the objects of the invention is to provide a manifold for an internal combustion engine in which fuel vaporizers are situated adjacent the engine intake ports.

10 Another object of the invention is to provide an intake manifold for an internal combustion engine in which the vaporizers are located at the lowest portions of the manifold and in position to intimately contact with 15 small quantities of liquid fuel therein.

Another object of the invention is to provide an intake manifold for an internal combustion engine that will have auxiliary liquid fuel vaporizers therein and a manually operated device for introducing fuel adjacent the vaporizers when the engine is at rest.

A further object of the invention is to provide an intake manifold for an internal combustion engine in which liquid fuel may be 25 both forcibly introduced and vaporized at points adjacent the engine intake ports.

Other objects will appear in the description to follow in which for the purposes of the present application I have illustrated one embodiment of the invention in the accompanying drawings in which:

Figure I is a side elevation of a portion of an internal combustion engine showing the improved manifold in place and showing a 35 suggested arrangement of the vaporizer and primer controls.

Fig. II is an enlarged sectional view of the vaporizer switch taken on line II-II of Fig. I.

Fig. III is an enlarged sectional view taken on line III-III of Fig. I.

Fig. IV is an enlarged section of the fuel primer.

Fig. V is a sectional view taken on line 45 V-V of Fig. IV, and

Fig. VI is an enlarged horizontal, sectional view of a portion of the manifold with one of the vaporizers in position and having the relative position of the engine cylinders 50 shown in broken lines.

Referring to the drawings in which like characters refer to like parts throughout the views, 1 is an internal combustion engine, to which is secured an intake manifold 2 for feeding the usual mixture of liquid fuel 55 and air to the engine, the mixture supply being led through a passage way in the engine from a carburetor (not shown) to approximately the middle of the manifold at 3. From the middle of the manifold two 60 branches 4 are led in opposite directions and have a slight downward slope toward the ends, at which they join the smaller Y-shaped portions 5 which coincide with the cylinder ports 6 as shown in Fig. VI. In each of the 65 branches 4 is a pocket 7 that opens into the branches at substantially their lowest points, which are preferably adjacent the intake ports 6.

Within pockets 7 are removable electrically 70 heated vaporizers 8 which are adapted to vaporize any liquid fuel collecting in pockets 7. The electric circuit for heating the vaporizer 8 is led from a suitable source of current 9 through a switch 10 to the vaporizer, and 75 from there back to the source through the engine frame. Switch 10 preferably has a spring controlled operating button for making electrical connection between terminals 12, one of which is connected to the vaporizer 80 wire 13 and the other to the current source 9 by means of a suitable wire 14.

Within pockets 7 are also located fuel inlet connections 15 which are preferably directed towards the vaporizers 8 at a slight 85 upward angle. Inlet connections 15 are connected by suitable piping 16A to a manually operated fuel primer 16 which is adapted to draw liquid fuel from a supply tank 17 through pipe 18 into the body of the primer 90 and to forcibly inject it through inlet connections 15 into the manifold 2. Any desired form of primer may be used, but I prefer to use the atomizing type. A well known primer that has been very satisfactory is 95 illustrated in Figs. V and VI, in which an outward movement of handle 19 draws with it plunger 20 and fills the body of the primer with fuel from the supply tank 17 through connection 21, having an inwardly opening 100

check valve 22. An inward movement of the handle forces the fuel past the outwardly opening check valve 23 into passage 21, past the spring loaded diaphragm 25 which serves to atomize the fuel, and delivers it in a finely divided condition through connection 26 and pipe 16A to the manifold 2.

The recommended operation of the control devices to secure satisfactory starting of an internal combustion engine that is equipped with the improved manifold, is to first operate the primer by withdrawing and forcing inwardly the handle 19. The result of this procedure is to force atomized fuel into the pockets 7 of the manifold 2 adjacent intake ports 6. A portion of this fuel will be sufficiently divided to be readily drawn into the intake ports but another portion will be condensed on the walls of the manifold and drain down the sloping branches 4 into the pockets 7. The drainage will occur immediately after the fuel has been injected so that the control switch 10 may be pushed in as soon as the primer has been operated, and should be held in contact for a short period, such as fifteen or twenty seconds and then released. The closing of the switch will cause the heating vaporizers to convert the fuel in the cups from a liquid to a vapor form, so that if the engine be turned over in the usual manner an explosive fuel mixture will be drawn into the cylinders and result in immediate starting of the engine.

It may be readily seen from the foregoing description that I have provided a manifold in which both the mechanical injection of the atomized fuel and the vaporization of the liquid fuel by heat takes place adjacent the engine intake ports. The location of the cups adjacent the intake ports is very desirable because the distance that the mixture is required to travel is decreased and the condensation and deposition of liquid fuel is reduced. My experience has been that it is practically impossible to entirely eliminate condensation, consequently I prefer to construct my manifold with a slight slope toward the pocket and drain all liquid fuel, that is deposited on the manifold walls, toward the vaporizer. It was found that the sloping construction had another advantage, which is that upon stopping the engine a small amount of fuel mixture will remain in the manifold which will later deposit on the walls and collect in the pockets for aiding a subsequent starting operation.

While I have shown and described somewhat in detail a particular embodiment of the invention, it is to be understood that this showing and description are illustrative only, and that I do not regard the invention as limited to the details of construction shown and described except insofar as I have included such limitations within the terms of the following claim.

I claim as my invention:

In an internal combustion engine, an intake manifold comprising a downwardly sloping portion, a branch adapted to feed a plurality of cylinders extending from the end of said downwardly sloping portion toward said engine, a fuel receiving downwardly extending pocket located near the junction of said branch with said manifold proper, and means operating independent of the operation of the engine for heating fuel in said pocket.

In testimony whereof, I affix my signature.

EDWARD E. HUNTINGTON.
